UNITED STATES PATENT OFFICE.

FRANK PARDEE, OF HAZLETON, PENNSYLVANIA.

SPIRAL SEPARATOR.

1,197,056.

Specification of Letters Patent.

Patented Sept. 5, 1916.

Application filed February 6, 1913, Serial No. 746,598. Renewed February 11, 1916. Serial No. 77,789.

To all whom it may concern:

Be it known that I, FRANK PARDEE, a citizen of the United States, and resident of the city of Hazleton, in the county of 5 Luzerne and State of Pennsylvania, have invented certain new and useful Improvements in Spiral Separators, of which the following is a specification, reference being had to the accompanying drawings.

10 The invention relates to spiral separators, such as are in general use in coal breakers, for removing slate and bone from the coal. These separators utilize gravity, centrifugal force and frictional resistance, to cause a 15 differential action on the mixed substances which are thereby separated from one another during transit over runways formed on the plates or jackets composing the structure. The spiral plates have a pitch toward 20 the center and toward the lower end or outlet of the apparatus; and it is also common to make deviated or retarding surfaces on the jackets or on certain working parts with which the materials come in contact. The 25 varieties of retarding surfaces tried out or heretofore utilized in connection with spiral separators have been numerous.

The present invention has relation to retarding surfaces of a creased formation for 30 directing and guiding the heavier materials on and along the runways, which it is designed they shall follow.

The object is to simplify the structural features, and to attain a more perfect separation.

35 The invention consists in a plate having divergent creases on a runway for the heavier materials, with the diverged terminals of the creases in proximity to uncreased 40 gravitational surfaces on the same runways; and in a spiral separator plate with such creased surfaces having their diverged terminals alternated transversely on the plate, or on an overlaying contactual part to which 45 they may be applied; and in the parts, features or combinations hereinafter more fully described and distinctly claimed, with such allowance for latitude as may be consistent with the substance or essence of the present 50 invention.

The plates or jackets on which the diverged creases are formed may be warped surfaces; or they may be surfaces partially warped and partially plane; or they may 55 be plane surfaces. The spiral may be composed wholly of plates of one such class or

another; or, of combinations made up from the several classes mentioned; and the successive plates may overlap downwardly or there may be gaps between them.

60 In the drawings Figure 1, is a side elevation of several plates or jackets forming the upper part of a spiral separator, and shows the flange for guiding the materials to the uppermost plate, and also the central post and supporting rods for several of the upper plates of a so called slate-thread. Fig. 2, is a plan view of two of the upper plates, the uppermost one of which has a perforated overlaying part also creased, 70 while the plate below it has an overlaying part with creases alternating laterally as respects their adjacent and divergent terminals. Fig. 3, is a section taken on the line 3, 3, of Fig. 2. In these three figures the jackets represented and their overlaying parts, are warped surfaces modified by perforations and creases. Fig. 4, is a plan view of a plate having a plane surface as distinguished from warped, and it is bent at its 80 lower edge so as to form an incline or drop extending inwardly toward the post. This figure shows such a plate as having an overlaying part with creases having divergent terminals alternating laterally. Fig. 5, is 85 a section taken on the line 5, 5, of Fig. 4. Fig. 6, is a lower edge view, looking up at the plate shown by the two previous figures. Fig. 7, is a plan view of a plane plate formed by bends or angles which makes an inwardly 90 extending gutter near its upper edge and allows the materials to drop from the plate above it. This figure shows creases diverging downwardly on the lower face of the gutter and also on the large surface below it. Fig. 8, is a cross section taken on the line 8, 8, of Fig. 7; and Fig. 9, is a cross section taken on the line 9, 9, of Fig. 7. In 95 Figs. 7, 8, and 9, no overlaying part is shown, the creases being formed directly on 100 certain parts of a one-piece plate.

In the drawings A, represents the central post which supports the spirally arranged jackets B, surrounding it. The mixed materials coming from a source of supply are 105 guided by the flange a, at the top, so that they enter the spiral proper with a given circular tendency. The working or contactual surface, on which the materials move, is on the upper side or face of the plates B, 110 or on the upper face of overlaying parts, if any. These plates and parts are supported

by rods *b*, projecting outwardly and upwardly from the central post *A*, the jackets and overlaying parts being secured to the rods *b*, by bolts passing through holes *b'*. These 5 structural features are common requisites or expedients in spiral separators.

On the plates, or on overlaying parts thereof divergent creased retarding and guiding surfaces *c*, *c*, *c*, are formed, preferably by an alternating displacement of the metal from the under and upper surface made during the process of manufacture. The creases *c*, may be curved as shown in Figs. 2, and 4, or they may be straight as 10 shown in Fig. 7; they may approach or become adjacent at their upper or at their lower ends; and they may diverge in an upward, downward, or lateral direction. Preferably one of the diverging creases *c*, follows 15 in a direction which would be spiral or around the post if continued throughout, and the crease which diverges from it takes a direction somewhat lateral so that if continued it would extend across the plate diagonally. In practice, however, the creases 20 preferably extend but a short distance on each plate, and produce surfaces which, in addition to their retarding effect, occasion a slight drop of the materials at the lower 25 edge of the plate or its overlay part or a similar effect, though less pronounced, when the heavier materials cross over the creases.

The spread of the creases may be in any 30 desired direction. The spread ends or diverged terminals of the creases terminate in proximity to uncreased gravitational surfaces on the same plate or runway, and the retarding and guiding effects are not continued to such an extent as to impair the force of 35 gravity which is given full sway on the uncreased surfaces with which the diverged terminals are in proximity. It is not essential but desirable to have a series of these 40 diverging and converging creases sufficient in number to extend laterally over the greater 45 part of the slate and bone runways.

In the form of spiral slate-threads shown 50 by Figs. 1, and 2, one or more of the upper plates has an overlay contactual part, which in addition to being creased is also perforated, thus affording a greater initial retardation of slate and bone and causing the slate, in particular, to seek its runway next to the post when near the upper end of the 55 spiral. The part of the plate not overlaid is in proximity to some of the diverged terminals of the creases shown. When the slate and bone have taken their proper runways they will not require retardation so

much as they will a proper guidance. The 60 formation of the creases *c*, *c*, is such as to give them a distinct guiding effect; and in a full length spiral these creases are interposed at such points and on such a number of plates as may continue the guiding effect 65 according to requirements.

It is to be observed that there is no definite rule which can be invariably followed in forming the creases; their length and number on any given plate, and the number of 70 plates used in the make-up of a spiral on which they are to be utilized, is necessarily variable. The conditions often differ with respect to the nature of the materials to be separated, and with respect to the state of 75 those materials as to being wet or dry. Modifications which cannot be properly set forth, but become apparent to the constructor and operator, are to be allowed for in the practical construction of a spiral separator. 80

Having thus described my invention, what I claim as new and desire to secure by Letters Patent is:—

1. A spiral separator plate having divergent creases on a runway for one of the heavier materials, said creases having their divergent terminals in proximity to uncreased gravitational contactual surfaces on the same runway. 85

2. A spiral separator plate having divergent creases on runways for the heavier materials, said creases having their divergent terminals alternated and disposed in proximity to uncreased gravitational contactual surfaces on the same runways. 90

3. A spiral separator plate having divergent creases on runways for the heavier materials, said creases being alternated and the surfaces between them perforated, whereby 100 greater retardation may be effected.

4. A spiral separator plate having an overlay part provided with divergent creases on a runway for the heavier materials, said overlay part being perforated and the diverged terminals of said creases being in proximity to gravitational uncreased contactual surfaces. 105

5. A spiral separator provided with plates having diverged creases on the runways for 110 the heavier materials, the diverged terminals of said creases being in proximity to uncreased gravitational surfaces on the same runways of the spiral.

FRANK PARDEE.
